[57]

ABSTRACT

An apparatus for making sand molds is disclosed, having a plurality of equally spaced stations, a pair of first and second mold chambers, with the first mold chamber being stationarily mounted and the second mold chamber pivoted to the first mold chamber. The chambers are rotated successively to the various stations where the steps of making sand molds are successively executed, such as filling with mold sand, compressing of the sand, removal of the mold halves and so on.

Also disclosed is a plate within a mold chamber with a plurality of passages leading through the plate into the mold chamber for passing compressed air therethrough to thoroughly mix the sand while it is being compressed within the mold chamber.

FIG. 7

APPARATUS FOR MAKING SAND MOLDS

BACKGROUND OF THE INVENTION

The present invention relates to an apparatus for making sand molds.

It is an object of the present invention to provide an apparatus for making sand molds which is simpler in design and operation, and lower in cost than heretofore known apparatus for making sand molds.

It is another object of this invention to provide an apparatus for making sand molds, which permits the production of several sand molds in one and the same machine simultaneously.

BRIEF DESCRIPTION OF THE DRAWING

The invention is illustrated by way of example in the attached drawings, in which:

FIG. 1 is a top view of the apparatus for making sand molds, according to the present invention;

FIG. 2 is a section along the line II—II of FIG. 1, showing the apparatus during the process of filling the mold chambers with mold sand;

FIG. 3 is a section taken along the line III—III of FIG. 1, showing the apparatus in the position in which the mold sand is compressed in the mold chambers;

FIG. 4 is a section taken along the line IV—IV of FIG. 1, and shows the machine in a position similar to FIG. 3, but with the pattern carrier removed from the mold chambers and with cores being inserted;

FIG. 5 is a section taken along the line V—V of FIG. 1 in which the one mold chamber has been placed on top of the other mold chamber and in which the mold in the upper mold chamber is in the process of being displaced into the lower mold chamber;

FIG. 6 is a side view of the mechanism for moving the right hand mold chamber of FIG. 4 into the position of FIG. 5;

FIG. 7 is a section taken along the line VII—VII of FIG. 1, and in which the completed mold has been lifted out of the lower mold chamber;

FIG. 8 is a section along the line VIII—VIII of FIG. 1, and in which the mold chambers and associated apparatus is returned to the initial starting position for a new cycle of operation of the machine.

DETAILED DESCRIPTION OF A PREFERRED EMBODIMENT

Referring now to the drawing in detail, the general structure of the apparatus according to the present invention is illustrated in FIG. 1 in which one and the same pair of sand molds are shown in different positions within the apparatus.

More specifically, the apparatus comprises a support 10 having two upstanding circular walls, an outer wall 12 and an inner wall 14. Outer wall 12 carries an annular ball bearing 16 with the lower race 18 thereof connected to the outer wall 12 while the upper race 20 supports an outer mold chamber 22. The upper race 20 carries at several places a small bracket 24 to which the mold chamber 22 is connected by means of bolts 26.

Similarly, the inner wall 14 carries an annular ball bearing 28. The lower race 30 thereof is connected to the inner circular wall 14. However, the inner mold chamber designated with the reference numeral 32 is not fixedly connected to the upper ball bearing race 34, but instead merely rests thereon.

The upper race 20 of ball bearing 16 is provided with a gear ring 36 which meshes with a worm 38. This worm is driven via a magnetic clutch 40 by a motor not shown. It will be evident that by driving worm 38 the upper bearing race 20 will rotate and thereby move the outer mold chamber 22 in counter-clockwise direction, as indicated by the arrow 42, into a plurality of positions or stations, six such stations being shown in FIG. 1. The mold chambers 22 and 32 are interconnected by hinges 44 and 46 and a pivot 48. Rotation of the outer mold chamber 22 will consequently result in rotation of the inner mold chamber 32 into the above mentioned plurality of different positions.

The outer mold chamber 22 has mounted therein a laminated plate 50 which is slidable within mold chamber 22 and has connected thereto two pins 52, each provided at the bottom with a ring 54. Similarly, the inner mold chamber 32 is provided with a laminated plate 56 having two pins 58 with rings 60.

In the position shown in FIG. 2, mold sand is gravity-fed through conduits 64 and 66 into the outer and inner mold chambers, in substantially equal amounts. This will fill the outer mold chamber 22 to a level 68 and the inner mold chamber 32 to a level 70 substantially coinciding with the top of the mold chamber 32. As shown in FIG. 2 a spacer ring 62 is provided in the inner mold chamber 32.

Rotation of ring 20 by worm 38 will move the two mold chambers in counter-clockwise direction by approximately 60° into the position illustrated in section in FIG. 3. At this second station, the sand in the outer and inner mold chambers 22 and 32 respectively is compressed by fluid motors 72 and 74, respectively having pistons 76 and 78. These pistons are provided with pattern carriers 80 and 82 respectively. In the embodiment illustrated in the drawing, pattern carrier 80 has elevations 84 which are semi-circular in cross-section and substantially rectangular in longitudinal section. Pattern carrier 82 is provided with similar elevations 86. Compression of the sand by the mold carriers 80 and 82 will form two mold halves 88 and 90 (see FIG. 4).

One important aspect of this invention is to be explained in connection with FIG. 3. The laminated plate 50 comprises an upper plate 92 and a lower plate 94, leaving a hollow chamber 96. The upper plate 92 is provided with a considerable number of perforations 98 substantially evenly distributed over the plate. Pin 52 has a hollow space 100 which communicates with chamber 96 and extends through ring 54. As further illustrated in FIG. 3, there is provided a hose 102 with a coupling 104 which in the position illustrated in FIG. 3 can sealingly engage ring 54, the seal in this instance being established by an O-ring 106.

Pattern carriers 80 and 82 are provided with a plurality of bores 108. The purpose of the bores 108, hose 102, and the bores 98 in plates 92, is the following: When compressing mold sand in mold chamber 22 or 32 it is easily compressed in regions designated in FIG. 3 with the reference numeral 110. However, in regions designated with the reference numeral 112 compression is very difficult and impossible depending on the shape of the patterns. In the embodiment illustrated in FIG. 3 this problem is not as pronounced as it could be if the distance between the areas 110 and 112 would be larger. However, in order to permit proper compression of the mold sand over the entire area of the pattern

carriers 80 and 82 and regardless of the form of the elevations 84 on the pattern carriers, air is introduced through hose 102, coupling 104 and chambers 96 as well as the bores 98 to thoroughly mix the sand while it is being compressed within the mold chamber. Excess air escapes through the bores 108 in pattern carriers 80 and 82. Once the compression has reached a certain stage, the supply of air through hose 102 is interrupted automatically by back-up pressure.

After compression of the mold sand, the pattern carriers 80 and 82 are withdrawn from the mold chambers 22 and 32, and via worm 38 the mold chambers are rotated by another 60° to the position shown in FIG. 4. In this position mold cores 114 are inserted by hand into the outer mold chamber 22.

Thereafter, the mold chambers are rotated by 60° into the next station of the apparatus, where the inner mold chamber 32 is tilted about pivot 48 into the position illustrated in FIG. 5, by means of the mechanism shown in FIG. 6. To this end, the inner mold chamber 32 is provided with hubs 116 on opposite sides thereof. They are engaged by a double-fork 118 connected to a piston rod 120 of a fluid motor 122 (FIGS. 1 and 6). Two guides 124 are connected to the cylinder 126 of the fluid motor 122 and form the guides for rods 128 of the mechanism. A cam 130 is connected to the rods 128. The mechanism furthermore comprises a roll 132.

Upon actuation of fluid motor 122 and engagement between fork 118 and hubs 116, the inner mold chamber 32 is pivoted in counter-clockwise direction, as seen in FIG. 6 and FIG. 5 since cam 130 is lifted over a stationary roll 132. In this position, a fluid motor 134 is actuated and its piston 136 and end plate 138 presses pins 58 downwardly and thereby displaces mold 90 from upper mold chamber 32 into the lower or outer mold chamber 22. Thereafter piston 136 is retracted, as is piston rod 120 by fluid motor 122. Fork 118 moves the mold chamber 32 in clockwise direction back onto the bearing ring 34.

Again, mold chambers 22 and 32 are rotated by 60° into the position illustrated in FIG. 7. In this position, a fluid motor (not shown) with a piston 140 pushes pins 52 upwardly until the laminated plate 50 reaches its end position slightly above the top of mold chamber 22. A pusher mechanism 142 pushes the complete mold with mold halves 88 and 90 and cores 114 onto a conveyor 144 for removal from the sand mold making machine.

Thereafter, the mold chambers are rotated again by 60° into the position shown in FIG. 8 in which two fluid motors 146 and 148 with pistons 150 and 152 respectively push plates 50 and 56 back into their original positions. Upon rotation of another 60° the machine has reached its starting position and a new cycle can begin.

The operation of the apparatus has been explained with reference to FIG. 1, as if two mold chambers were in different positions, each spaced 60° from the other. However, simultaneously six different mold chamber pairs could be processed within the machine. One mold chamber pair would be in the starting position, another in the position 60° offset in counter-clockwise direction, where sand is being introduced into the mold chambers, another pair in the position where the cores are being placed within the mold chambers, and so on.

It is to be understood that the above description illustrates one example only of a number of different embodiments within the scope of this invention. Thus, the

number of stations or mold pairs within the apparatus could be increased or reduced depending on requirements.

I claim:

- 5 1. An apparatus for making sand molds, comprising: frame means, support means rotatably mounted on said frame means, means for rotating said support means in a substantially horizontal plane to a plurality of substantially equally spaced stations about said frame means, at least one pair of first and second mold chamber means, pivot means interconnecting the first and second mold chamber means of each pair, said first mold chamber means of each pair being stationarily mounted on said support means, first means arranged 10 at a first one of said stations for introducing mold sand into said mold chamber means, second means arranged at a second one of said stations for compressing the mold sand in said mold chamber means to form mold halves, third means arranged following said second means for pivoting one of said first and second mold chamber means of each pair about said pivot means from a first position next to said one mold chamber means to a second, inverted position above said one mold chamber means, and for returning the same to its 15 first position, fourth means arranged at a third station for displacing the mold half in said other mold chamber means of each said pair into said one mold chamber means of each said pair while the other mold chamber means is above said one mold chamber means, and fifth means arranged at a fifth one of said stations for removing the two mold halves from said one mold chamber means of each said pair.
- 20 2. An apparatus according to claim 1, wherein said support means form a circle, ball bearing means rotatably supporting said support means on said frame means, said stations being arranged at equally spaced intervals on said circle.
- 25 3. An apparatus according to claim 1, comprising plate means in each of said mold chamber means, and wherein said fifth means is adapted to move said plate means in said one mold chamber means above said one mold chamber means.
- 30 4. An apparatus according to claim 3, wherein said second means includes fluid motor means and pattern carrier means connected to each fluid motor means for shaping the mold sand in the respective mold chamber means when the mold sand therein is being compressed.
- 35 5. An apparatus according to claim 4, wherein each plate means is provided with a hollow chamber therein, a plurality of passages leading from said hollow chamber through said plate means into the respective mold chamber means, and conduit means leading from the exterior of said plate means into said hollow chamber, said conduit means being adapted to be connected to a source of fluid under pressure for introducing such fluid under pressure through said conduit means, hollow chamber and passages into the respective mold chamber means while the mold sand in the latter is being compressed in said second station to thereby assure even compression of the mold sand around said pattern carrier means.
- 40 6. An apparatus according to claim 1, comprising additional support means at said second station beneath said mold chamber means.
- 45 7. An apparatus according to claim 1, wherein said fluid means comprises fork means adapted to engage

said other mold chamber means of each pair, fluid motor means operatively connected to said fork means, and cam means associated with said fork means for controlling movement of the latter by said fluid motor means connected thereto to pivot said other mold chamber means of each pair about said pivot means to said second, inverted position and to return the same to said first position.

8. An apparatus according to claim 1, which includes a station between said second and third stations for permitting insertion of cores into the mold half in said one mold chamber means.

9. An apparatus according to claim 3, which includes conveyor means located at said fifth station, and pusher means at said fifth station for transferring the two mold halves onto said conveyor means from said plate means above said one mold chamber means.

10. An apparatus according to claim 1, wherein the number of pairs of mold chamber means corresponds to the number of said stations.

11. An apparatus according to claim 1, wherein said third means is arranged at said third station.

12. In an apparatus for making sand molds, mold chamber means comprising upstanding side walls, and a bottom wall extending substantially perpendicularly to said side walls, and plate means in said mold chamber means extending substantially parallel to said bottom wall and movable from adjacent said bottom wall along said side walls in substantially close contact therewith, said plate means being provided with a hollow chamber therein, a plurality of passages leading from said hollow chamber through said plate means into said mold chamber means, and conduit means leading from the exterior of said plate means into said hollow chamber, said conduit means being adapted to be connected to a source of fluid under pressure for introducing such fluid under pressure through said conduit means, hollow chamber and passages into said mold chamber means.
